THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,275,200.

Specification of Letters Patent. Patented Aug. 13, 1918.

Application filed December 15, 1914. Serial No. 877,337.

To all whom it may concern:

Be it known that I, THOMAS E. BARNUM, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

This invention relates to electric switches and more particularly to those of the pressure operated type.

Such switches are commonly employed to automatically control suitable apparatus in accordance with predetermined governing pressures and it is customary to provide means for effecting operation of the switch to open or close circuit when such pressure rises above a certain maximum and to close or open circuit when the pressure falls below a certain minimum.

It is one of the objects of this invention to provide simple and improved means for varying at will the pressure at which the switch will operate in one direction without affecting the pressure limit at which the switch will operate in the other direction.

Other objects and advantages will appear hereinafter in connection with a description of the accompanying drawing which illustrates a typical embodiment of the invention, and in which—

Figure 1 is a plan view of an electric switch, and

Fig. 2 is a side view thereof partially in section, and

Fig. 3 is a detail perspective view.

The pressure operated switch illustrated comprises in general a diaphragm pressure device A arranged to move a lever 1 for actuating a member 2 to open or close an electric circuit between a movable contact 3 and a stationary contact 4.

Referring more specifically to the drawing, the several parts of the switch mechanism are mounted upon a supporting frame comprising a base part 5 and a part 6 having complementary recessed portions forming a pressure chamber 7 at one end. A diaphragm 8 of suitable material is disposed within said chamber and is clamped between the parts of the frame by connecting screws 9. Resting upon said diaphragm 55 and projecting centrally through the cover

of the pressure chamber is a piston 10 normally biased inwardly by a main coil spring 11 confined between the outer end of the piston and a cap plate 12 slidably mounted on spaced uprights 13 and adjustable thereon to vary the normal tension of said spring. The upper part of the frame 6 has also an elongated integral extension 14 on which is mounted a rectangular insulating base 15 carrying the stationary contact 4 and other current conducting parts of the mechanism.

The operated contact member of the switch comprises a metal plate 16 having secured thereto a yielding extension 17 with the contact tip 3 movable to engage the stationary contact on the insulating base. The plate 16 is provided on opposite sides with offset portions 18 having alined knife edges 19 seated in notches of two spaced posts 20 secured to the insulating base 15, said member being retained in position by a coil spring 21 disposed within a slot in the plate and connecting the end of the latter with the extremity of the lever 1 which also works in the slot of the contact plate. Said lever 1 and spring 21 in addition to holding the contact member in place also constitute the operating means therefor, the extremity of said lever being movable to carry the plane of tension of said spring across the axis of the operated member and thereby effect pivotal movement of the latter, as will appear.

In order to insure an effective snap actuation of the contact member in opening circuit, there is provided a latch 22 pivoted to a fixed post 23 and projecting through the contact plate. Said latch is biased by a spring 24 to engage and hold the plate when in closed circuit position, said spring being inclosed in the post 23 and working against an offset arm 25 of the latch. The operating lever has an adjustable pin 26 at its extremity movable to strike the arm 25 of the latch and thereby trip the latter to free the contact plate. This operation, however, is not effected until the operated member has moved the spring 21 across the axis of the contact plate to thereby exert its force toward oscillating said contact to open circuit position. Accordingly when the latch is tripped the energy of the coil spring 21 is suddenly released and insures a quick movement of the operated lever. It is to be noted also that the snap movement of the

operated lever does not occur in either direction until after the operating lever has moved through a major portion of its travel.

The switch operating lever is preferably

- 5 formed in two sections 27 and 27^a fixed together by bolts 28 but insulated from each other by suitable washers 29. The lever is pivotally mounted upon an upstanding lug 30 of the frame 6 and is also pivotally
- 10 hooked over a spindle extending through the pressure piston 10, so that as pressure in the chamber 7 rises above a predetermined point and the piston is moved outwardly the free extremity of said lever is
- 15 rocked inwardly and effects opening of the switch as described.

As above mentioned, the degree of compression of the main spring 11 may be adjusted at will by the sliding cap 12 to vary 20 equally the pressure limits at which the mechanism is set to open and close circuit. Further means are provided to vary the pressure limit at which the switch is set to open circuit independently of and without 25 affecting the preselected pressure limit at which the switch will close circuit. It will thus be observed that the range between the pressure limits at which the switch will operate, may be increased or diminished at will. In the form shown, the 30 means to vary a single pressure limit comprises a pin 31 loosely journaled through the elongated extension 14 of the supporting frame and disposed in the path of movement of an integral lug 32 of the operating lever when the latter is moved in response to increased pressure in the chamber 7. Said pin 31 is biased outwardly by a coil spring 33 and carries at 35 its lower end a fixed collar 34 which abuts the frame and accordingly maintains the pin head in a definite normal position. The spring 33 is confined between a shoulder 35 at the head of the pin and a loose plate 36 40 having lateral extensions 37 through which two adjustable screws 38 are threaded to rest in bearings 39 on the supporting frame. By adjustment of said screws it will be apparent that the plate 36 may be raised or lowered at will to thereby increase or 45 diminish the normal compression or tension of the spring 33. In practice the lower extremity of the screws 38 are beveled and the bearings thereof provided with V-shaped 50 recesses to receive the same so that the beveled tips of said screws rest against the sides of the recesses and are thus yieldably locked against rotation. The outer end of the pin 31 is preferably recessed and a coil spring 55 40 disposed therein and confined between the bottom of said recess and the lug 32 of the operating lever, said spring being subservient to the load spring 33 and accordingly ineffective to move the pin 31 downwardly but of sufficient strength to maintain

the hooked extremity of the operating lever 27 held against its pivotal axis on the portion 10 and take up any lost motion in the bearings.

It is to be understood that the total travel 70 of the operating member from opposite extreme positions to its positions at which the snap actuations of the operated member occur is greater than the distance between said extreme positions. There is accordingly an intermediate neutral travel 75 range of the operating member in which the position of the operated member depends upon the direction from which the operating member is proceeding, *i. e.*, if the 80 operating member is moving away from its travel limit with the switch closed, the switch will remain closed until said operating member reaches a position where the switch would be open if said member were 85 moving from its opposite travel limit. The head of the pin 31 is biased to extend within this neutral travel range of the lug 32 on the operating lever. Accordingly when the switch is operating to open circuit, said lug 32 strikes said pin prior to 90 tripping of the latch 22 and therefore prior to snap movement of the contact plate. Thus the spring 33 acts to oppose movement 95 of the switch in opening. In closing, however, said lug moves out of engagement with the head of the pin before the operating lever is moved to carry the plane of tension 100 of the coil spring 21 across the axis of the operated contact lever. Thus in closing circuit the coil spring 33 and pin 31 biased thereby 105 neither oppose nor assist the main spring 11. Accordingly, by varying the compression of the spring 33 through the plate 36 and screws 38 as described, the pressure limit at which the switch is set to open 110 circuit may be varied at will without affecting in any degree the preselected pressure limit at which the spring is set to close circuit and without varying the travel of the 115 operating member requisite to effect either operation. For example, assuming the main coil spring 11 to be adjusted so that the switch is set to open circuit when the pressure in the chamber 7 rises to eighty pounds 120 and to close circuit when said pressure falls to sixty pounds, it is apparent by increasing the tension of the load spring 33 the opening pressure limit of the switch may be increased, for example, to ninety pounds 125 while closing pressure limit of the switch still remains at sixty pounds. The main spring 11 may of course be also regulated independently of the load spring to vary equally the opening and closing pressure limit of the spring, *e. g.* if this spring is compressed to a greater degree the opening pressure limit of the switch may be increased to one hundred pounds but with an attendant equal increase of the closing pres- 130

sure limit to eighty pounds. A further adjustment of the mechanism may be effected by the tripping screw 26 on the operating lever. This adjustment, however, varies the 5 travel of the operating lever required to trip the latch 22 for releasing the contact lever.

It may be noted that the structure as a whole is compact, sturdy and reliable. The 10 various parts of the mechanism to which access may be desired, that is, the terminal connections, the adjusting means of the main spring 11 and load spring 33, and the moving elements of the switch, are all arranged on the free side of the device.

15 What I claim as new and desire to secure by Letters Patent is:—

1. In a pressure responsive switch, in combination, coöperating contacts, a fluid pressure device, a member actuated by said 20 device, an operative connection between said member and one of said contacts for effecting engagement and disengagement of said contacts upon movement of said member to predetermined critical positions, and 25 means independent of said connection for providing range adjustment of the pressure variation in said device, required for movement of said member from one predetermined critical position to the other.

30 2. In a pressure responsive switch, in combination, coöperating contacts, a fluid pressure device, a member actuated by said device, an operative connection between said member and one of said contacts for effecting 35 engagement and disengagement of said contacts upon reverse movements of said member to predetermined critical positions and separate means acting directly upon said member and opposing movement thereof 40 from one of its critical positions toward the other to reduce its sensitiveness of response to said device, said member being free from influence by said means during final return movement to said former critical position.

45 3. In a pressure responsive switch, in combination, a switch including a pivoted contact member, a fluid pressure device, an operating member actuated by said device, a spring connecting said operating member 50 and said contact member whereby the for-

mer upon reverse movements to predetermined critical positions actuates the latter in opposite directions and a spring pressed device acting directly upon said operating member and opposing movement of the 55 same from one of its critical positions toward the other to reduce its sensitiveness of response to said fluid pressure device, said spring pressed device being adjustable to vary such reduction in sensitiveness and 60 being arranged to free said operating member from its influence during final return movement thereof to said former critical position.

4. In a pressure actuated switch, in combination, an elongated frame, a switch including a pivoted contact member mounted at one end thereof, a pressure responsive device mounted on the other end of said frame, an elongated operating member 70 pivoted to said frame and having one end operatively connected to said device, an energy storing connection between said contact member and the free end of said switch operating member for effecting a delayed 75 movement of the former in response to movement of the latter, a pivoted latch biased to automatically engage and lock said contact member in closed position, said latch being tripped by said operating member during movement thereof into one of its extreme positions, and a spring pressed device carried by said frame and arranged to oppose movement of said operating member toward said extreme position to reduce 80 the sensitiveness of response of said operating member to said device, said spring pressed device being adjustable to vary such reduction in sensitiveness and being arranged to act on said operating member only 85 90 after the same has moved through a part of its range.

In witness whereof, I have hereunto subscribed my name in the presence of two witnesses.

THOMAS E. BARNUM.
